Primary Examiner — Cynthia Ramirez*Assistant Examiner* — Laura H Yu(74) Attorney, Agent, or Firm — Sheppard, Mullin,
Richter & Hampton LLP(57) CLAIM

I claim the ornamental design for a shoe, as shown and described.

DESCRIPTION

FIG. 1 is a front perspective view of a shoe showing my new design.

FIG. 2 is a front elevational view of the shoe of FIG. 1.

FIG. 3 is a rear elevational view of the shoe of FIG. 1.

FIG. 4 is a left side elevational view of the shoe of FIG. 1.

FIG. 5 is a right side elevational view of the shoe of FIG. 1.

FIG. 6 is a top plan view of the shoe of FIG. 1; and,

FIG. 7 is a bottom plan view of the shoe of FIG. 1.

The broken lines depicting the remainder of the shoe, in FIGS. 1-7, are for the purpose of illustrating portions of the shoe that form no part of the claimed design.
